UNITED STATES PATENT OFFICE

2,410,186

SLIPPER

Francis J. Shields, Bombay, N. Y.

Application March 2, 1944, Serial No. 524,683

1 Claim. (Cl. 36—11)

1
This invention relates to new and useful improvements in a slipper.

More specifically, the invention proposes the construction of a slipper adapted to be worn as a slipper and characterized by a sheepskin member having its wool outside and stitched at the front and back to form the sole, front, sides and back of the slipper.

Still another object of the invention proposes the provision of a sheepskin having its wool outside and stitched to the vamp edges of the sheepskin member in a manner to complete the formation of the slipper and retain it in position upon the foot.

Still another object of the invention proposes the application of tape material for extending along all of the free edges of the slipper in a manner to give it a finished appearance.

Still further the invention proposes adhesively applying fleece-like cloth material to all interior surfaces of the slipper in a manner to add to the warmth thereof when worn.

A further object of the invention proposes the provision of adjustable laces between the free edges of the sheepskin vamp and the sheepskin member in a manner to permit these laces to be adjusted for controlling the relationship between its adjacent edges to cause the shoe to fit more snugly upon the foot.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure—

Fig. 1 is a perspective view of a slipper constructed in accordance with the invention.

Fig. 2 is an enlarged partial vertical sectional view taken on the line 2—2 of Fig. 1.

Fig. 3 is a developed view from which the sheepskin member is formed.

Fig. 4 is a developed view of the sheepskin plug.

Fig. 5 is a side elevational view of a shoe constructed in accordance with a modification of this invention.

Fig. 6 is a partial plan view looking in the direction of the line 6—6 of Fig. 5.

The slipper, according to this invention, is constructed of a sheepskin member 10 which has its wool directed outside and which is stitched together at its front edge 11 and at its back edge 12 forming the sole, front, sides and back of the shoe. A sheepskin plug 13 also having its wool

directed outwards is stitched to the vamp edges of the sheepskin member 10 at the front 14 of this member.

Adhesively secured to all inside faces of the sheepskin member 10 and the sheepskin plug 13 is a layer of wool fleece material 15. Mucilage 16 for securing the fleece material in position is secured between the adjacent edges of the sheepskin and the fleece material 15. In constructing the shoe the fleece material 15 is preferably secured to the back face of the sheepskin material before the blanks 10 and 13 are cut therefrom.

All exposed edges of the sheepskin member 10 and the sheepskin vamp 13 are finished by the application of tape material 17 which is held in position by means of a line of stitches 18.

In the modification of the invention shown in Figs. 5 and 6, the construction of the slipper is similar to that previously described except for the provision of laces 19 which extend through aligned openings 20 formed in the free adjacent edges of the member 10 and the plug 13 and which are adapted to have their ends tied into a bow 21. The laces 19 may be adjusted for reducing the diameter of the shoe across the instep of the foot in a manner to cause the shoe to fit more snugly upon the foot.

In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

A slipper comprising a member forming the sole, front, sides, and back of the slipper, a plug stitched to the top front edges of said member, and said plug having free edges at the instep area, said plug and member along said free edges being provided with a series of eyelets, means for adjustably connecting said free edges together to control the diameter of the slipper at the instep area, said means comprising separate laces extending between the free edges and adapted to have their ends tied together in adjustable positions.

FRANCIS J. SHIELDS.
